(57) **CLAIM**

An ornamental design for a spanner wrench, as shown and described.

DESCRIPTION

FIG. 1 is a first perspective view of a spanner wrench, in accordance with an embodiment;

FIG. 2 is a second perspective view of the spanner wrench of FIG. 1;

FIG. 3 is a third perspective view of the spanner wrench of FIG. 1;

FIG. 4 is a third perspective view of the spanner wrench of FIG. 1;

FIG. 5 is a left side view of the spanner wrench of FIG. 1; FIG. 6 is a right side view of the spanner wrench of FIG. 1; FIG. 7 is a left side view of the spanner wrench of FIG. 1 in a first position with respect to a handle shown in broken lines;

FIG. 8 is a left side view of the spanner wrench of FIG. 1 in a second position with respect to a handle shown in broken lines; and,

FIG. 9 is a left side view of the spanner wrench of FIG. 1 in a third position with respect to a handle shown in broken lines.

The broken lines depicted in FIG. 7-9 are for the purpose of illustrating a handle feature and orientations the spanner wrench with respect to the handle feature and form no part of the claimed design.
